UNITED STATES PATENT OFFICE

2,581,838

DOOR LOCK

Thomas C. Dingman, South Bend, Ind., assignor
to The Studebaker Corporation, South Bend,
Ind., a corporation of Delaware

Application March 8, 1946, Serial No. 653,096

1 Claim. (Cl. 292—280)

1

My present invention relates to an improvement in a door lock comprising a latch mechanism of a character providing for engagement of one or more cams with a rotatable bolt for urging the latter into engagement with a stationary keeper.

Door latch mechanisms of a type comprising a rotatable bolt adapted to have releasable engagement with a relatively stationary keeper and safety catch member therefor have gone into wide spread use in the automotive industry in recent years. Generally in such latch mechanisms one or more cams are spring loaded for biasing them into engagement with the bolt. When a plurality of cams are employed they are generally of different lengths to provide for progressive engagement with the bolt with the springs being arranged so that the vibration of the vehicle during movement thereof serves to more positively engage the bolt with the keeper when the latch mechanism is in locked position.

These latch mechanisms of the prior art usually comprise a pair of door handle members arranged interiorly and exteriorly of the car door which are mounted for pivotal movement about a horizontally extending axis for rotating the cams against the force of the biasing springs to withdraw the cams from engagement with the bolt in order to free the latter from the keeper.

It has been proposed in the designing of automobile bodies to provide a door handle of the pull type i.e., mounted for pivotal movement about a substantially vertically extending axis for unlatching the latch mechanism externally of the car. Also it is desirable to provide push button means internally of the car arranged substantially flush with the interior surface of the door to avoid the use of present forms of internal door handles which project interiorly of the car and form undesirable obstructions.

It is an object of my invention to provide a latch mechanism of the type above described, embodying a novel form of slide member adapted to be actuated either interiorly or exteriorly of the vehicle, and which slide member is effective to cause rotation of one or more cam members against the force of spring means for normally biasing cam means into engagement with a rotatable bolt adapted to have releasable locking engagement with a relatively stationary keeper.

A further object of my invention is to provide a latch mechanism comprising a rotatable bolt, spring loaded cam means for engaging the bolt to restrain the latter against rotation, and a slide member associated with the cam means and

2

movable rectilinearly for rotating the cam means against the force of the spring means to release the cam means from engagement with the bolt.

A further object is to provide a latch mechanism as aforesaid in which a slot and pin connecting means interconnects the cam means and the slide member whereby rotation of the cam member is adapted to be effected by rectilinear movement of the slide member.

10 A further object is to provide a latch mechanism as aforesaid comprising a plurality of cam members normally individually spring loaded for engagement with a rotatable bolt, and in which one of the cam members is adapted to have connection with the slide member for effecting movement of it against the force of its associated spring, and in which the latter cam member is formed to provide for the rotation of the other cam members against the forces of the springs 20 associated therewith away from the bolt to release the same.

A further object of my invention is to provide a latch mechanism in which a cam means and bolt are mounted for rotation about fixed substantially parallel axes and in which a slide member is arranged for rectilinear movement transversely of the axes of the bolt and cam means, and inter-connected with the cam means for rotating the same against the force of spring means normally biasing the cam means into engagement with the bolt to release the latter.

A further object of my invention is to provide a latch mechanism as last aforesaid in which push button means is adapted to have connection with the slide member for effecting movement of the cam means from its normal position upon actuation of the push button means to release the bolt.

A still further object of my invention is to provide a latch mechanism comprising a rotatable bolt, spring loaded cam means for normally restraining the bolt against rotation, a slide member having connection with the cam means and mounted for rectilinear movement, and a handle lever of the pull type pivoted intermediate its ends on an axis normal to the axes of the bolt and cam means, and which handle is adapted to be rotated about its axis to engage the slide member to effect rectilinear movement 50 of the latter to release the cam means from the bolt.

A further object of my invention is to provide a latch mechanism of the character hereinabove referred to in which a spring loaded cam normally engaged with a bolt for restraining move-

ment of the latter is adapted to be released by rectilinear movement of a slide member having connection with the cam member selectively upon the actuation of a push button means or of a handle means.

A further object of my invention is to provide a latch mechanism embodying a rectilinearly moveable slide member for effecting the release of a spring loaded cam means from a bolt of the latch mechanism in which manually operable lock means is provided for preventing rectilinear movement of the slide member.

The above and other objects and advantages of my invention will appear from the detail description.

Now in order to acquaint those skilled in the art with the manner of construction and utilizing latch mechanisms in accordance with my invention, I shall describe in connection with the accompanying drawings a preferred embodiment of my invention.

In the drawings:

Figure 1 is a partial side elevational view of a pair of doors of an automotive vehicle illustrating the location and positioning of the latch mechanism of my present invention;

Figure 2 is a view taken substantially on the line 2-2 of Figure 1 looking in the direction indicated by the arrows, showing in transverse section the construction of the door of Figure 1, and illustrating in plan a latch mechanism constructed in accordance with my invention;

Figure 3 is a side elevational view of the latch mechanism shown in Figure 1 of the side thereof facing the exterior panel of the car door with this view being taken substantially on the line 3-3 of Figure 4 looking in the direction indicated by the arrows;

Figure 4 is an end elevational view taken substantially on the line 4-4 of Figure 3 looking at the end of the latch mechanism adapted to be disposed in juxtaposition of the edge of the door;

Figure 5 is a detail vertical sectional view taken substantially on the line 5-5 of Figure 2 looking in the direction indicated by the arrows with the end portion of a panel member extending transversely of the door inwardly of the latch mechanism removed, and illustrating the push button means disposed interiorly of the door and pull type handle lever means disposed exteriorly of the door of the latch mechanism for actuating the same.

Figure 6 is a detail vertical sectional view taken substantially on line 6-6 of Figure 5 looking in the direction indicated by the arrows;

Figure 7 is an elevational view of the upper portion of the latch mechanism facing the outer surface of the edge of the door, and illustrating the assembly therewith of manually operable means for preventing actuation of the latch mechanism; and

Figure 8 is a detailed horizontal sectional view taken substantially on the line 8-8 of Figure 7 looking in the direction indicated by the arrows.

Referring now to the drawings, I have shown in Figure 1 a portion of a pair of hinged doors 9-9 in which each of the doors 9-9 is provided with a latch mechanism adapted to have releasable engagement with a stationary keeper carried by a door post extending substantially vertically between the edges of the pair of doors 9-9 opposite the hinged edges thereof. This construction is conventional in the art. It will be ob-

served that the latch mechanism shown in Figures 2 through 8 has been shown in relation to the position of the latch mechanism in the door 9 at the left of Figure 1, but it will be understood that the latch mechanism in the door 9 to the right of Figure 1 is of identical construction but in reverse relation to that shown in the several figures of the drawings.

Referring now to Figure 2 it will be observed that the door 9 comprises a suitably formed interior sheet metal panel 14, and an exterior panel 15 with the panels 14 and 15 adjacent the free edge of the door 9 being arranged with the free end of the panel 14 enclosed between the folded end 16 of the panel 15. The panel member 14 forming the side edge of the door is recessed at 17 to provide for the reception of the latch mechanism 18 of my invention. The outer sheet metal panel 15 is recessed as shown at 19 for the reception of a door handle 20 with the recess 19 being formed so that the handle 20 when disposed in its normal position therein lies substantially flush with the outer surface of the car door. The handle 20 is of the pull type and is mounted for pivotal movement intermediate its ends about a substantially vertically extending pin 21. The long arm 22 of the handle 20 is adapted to be grasped by placing of the hand into the recess 19 and swung in a counter-clockwise direction about pivot pin 21 as viewed in Figure 2 to engage the free end of the short arm 23 thereof with the end 24 of a slide member 25 referred to in greater detail hereinafter.

It will be observed as most clearly shown in Figures 2 to 4, that the latch mechanism of my invention comprises a latch facing plate 27 which together with a spaced plate member 28 form a frame for supporting certain of the mechanism of the latch. The latch facing plate 27 is provided with a plurality of bolt holes 30 for mounting the frame in the recess 17 in the edge of the door. A bolt 31 is rotatably mounted about a horizontally extending pin 32, the opposite ends of which are secured in the plate member 28 and in the cup shaped member 33 secured to extend outwardly of the latch facing plate 27 at the lower end thereof, as by spot welding of a radially extending flange 33' at the inner surface of the plate member 27. The rotatable bolt 31 comprises a pair of prong wheels 34 and 35 with the prong wheel 34 extending outwardly of the latch facing plate 27 and disposed partially within the cup member 33. The prong wheel 34 is adapted to have releasable engagement with the stationary keeper 12 (shown in dotted outline in Figure 4) carried by the door post which is adapted to be received between the prong wheel 34 and the abutment member 36 extending outwardly of the latch facing plate 27. The prong wheel 35 is disposed between the latch facing plate 27 and the plate member 28 and as shown it is adapted to be engaged by a plurality of cams 43, 44 and 45 of slightly progressing increasing lengths, and which cams are mounted for pivotal movement about a pin 42 extending between the latch facing plate 27 and the panel member 28 and through the abutment member 36. The outer ends of the pin 42 are peened or riveted to provide a fixed axis for the cam members, and for mounting of the abutment member 36 upon the outer face of the latch facing plate 27 as shown. A plurality of springs 47, 48 and 49 are provided one each for each of the cam members 43, 44 and 45 respectively, which springs at one end are sup-

ported between a pair of lugs 52—52 struck up from a plate member 53 secured to the inner face of the latch facing plate 27. The springs 47, 48 and 49 are arranged for normally urging the cam members 43, 44 and 45 in a clockwise direction as viewed in Figure 4 into engagement with a prong of the rotor or prong wheel 35 of the bolt 31 to urge the prong wheel 34 thereof into engagement with the keeper 12. The cam 45 as shown is provided with an upwardly extending portion 56 having a slot 57 therein through which a pin 58 fixed to the slide member 25 extends. The slide member 25 is adapted to have rectilinear sliding movement in a guide way formed by the upper edge 60 of the plate member 53 and a guide bar 62 disposed along the upper edge of the slide member 25. Upon movement of the slide member 25 to the left as viewed, in Figures 4 and 5, it will be observed that the cam member 45 will be caused to be rotated about its axis on the pin 42 in a counter-clockwise direction against the force of spring 49 releasing the cam member from engagement with the prong wheel member 35 of the bolt 31. The cam member 45 along one edge thereof adjacent its pivotal mounting on the pin 42 (as best shown in Figure 8) is provided with an angular flanged portion 66 bent inwardly toward latch facing plate 27 and behind the cam members 43 and 44 for rotating them in a counter-clockwise direction against the force of springs 47 and 48 upon counter-clockwise rotation being imparted to the cam member 45 by rectilinear movement of slide member 25.

As previously related rectilinear sliding movement of the slide member 25 may be effective by grasping of the long arm 22 of the handle 20 and rotating it about the pivot 21 in a counter-clockwise direction as viewed in Figure 2 which movement of the handle 20 is effective to cause the free end of the short arm 23 thereof to engage the end 24 of the slide member 25, which in turn effects limited counter-clockwise rotation of the cam 45 as viewed in Figure 4 to release this cam and the cams 43 and 44 from engagement with prong wheel portion 35 of the rotatable bolt 31. Upon release of the prong wheel member 35 the prong wheel portion 34 of the bolt 31 may be released from engagement with the keeper 12 after which the door 9 may be opened by continued pulling of the handle 20.

Referring now to Figure 5 I have shown a push button means indicated generally at 70 and which comprises a push button 71 of known construction mounted for reciprocable movement in a shell 72 suitably secured in the interior panel 14 of the door. The spring 73 normally maintains the push button 71 in its inoperative position as shown in Figure 5. Upon depression of push button 71 with the thumb or otherwise it is caused to be moved to the right as viewed in Figure 5 with the closed end thereof engaging the free end of a link 75 which is connected at its other end to one end of a horizontally extending rod 76 which as shown in Figure 2 is mounted for rotation in a pair of bearing members 77—77 suitably secured internally of the door and to the panel member 14 thereof. A link 78 is secured to the other end of the rod 76 and is provided with a slot 79 in its free end into which the pin 58 fixed to the slide member 25 extends. Thus upon movement of the push button 71 inwardly of the door the link 75, as viewed in Figure 5, is caused to be rotated in a clockwise direction imparting clockwise rotation to the rod 76 and the link 78 at the other end thereof and

which through the connection of the link 78 with the pin 58 of the slide member 25 causes the slide member 25 to move to the left as viewed in this figure causing the cam member 45 to rotate about its axis in a counter-clockwise direction together with the pair of cam members 43 and 44 to release the prong wheel member 35 of the bolt 31 as previously described.

It will thus be observed that rectilinear sliding movement is adapted to be imparted to the slide member 25, selectively, by either the handle means 20, or the push button means 70 to withdraw the cams from the bolt and to release the bolt 31 from the keeper 12 and effect opening of the door 9 either exteriorly or interiorly of the vehicle.

Reference may now be had to Figures 5 through 8 from which it will be observed that I have also embodied a manually operable lock means 80 for preventing the rectilinear movement of the slide member 25 by actuation of either the handle means 20 or the push button means 70. The lock means comprises a substantially vertically slidable rod 81 having connection at the lower end thereof with a locking member 83. The locking member 83 is adapted to be reciprocated substantially vertically by grasping of the knob 84 at the upper end of the rod 81 to slide the lock member in or out of position for engaging the inner flanged end 86 of the slide member 25. The inside corner edge of the latch facing plate 27 and the guide bar 62 are arranged to provide for guiding of the lock bar vertically in and out of position for engagement with the out turned flanged end 86 of the slide member 25. Thus upon the depressing of the knob 84 the rod 81 effects sliding movement of the locking member 83 downwardly to a position where it will be abutted by the out turned flanged end 86 of the slide bar 25 upon manipulation of either the handle means 20 or the push button means 70 to prevent release of the cam members from camming engagement with the prong wheel portion 35 of the rotatable bolt 31.

While I have shown what I consider to be the preferred embodiment of my invention it will be understood that various rearrangements and modifications may be made therein without departing from the spirit and scope of my invention.

I claim:

In a latch mechanism for use with automobile doors or the like, a face plate member designed to mount said mechanism, a second plate member mounted to said face plate but spaced therefrom in parallel relation thereto, a pair of prong wheels mounted one between said two plates and one exteriorly of said face plate for simultaneous and interdependent rotative movement on a horizontally disposed pin member reaching between said two plates, a plurality of vertically disposed cam arms of progressively increasing lengths pivotally connected to said face plate, spring means normally urging said cam arms into engagement with said prong wheel disposed between said two plates to normally prevent rotative movement of both of said prong wheels, a horizontally disposed slide bar mounted for rectilinear sliding movement between said two plates, above said arms and in operative engagement therewith for periodically pivoting said cam arms in an arcuate path against the force of said spring means to release said prong wheels, said sliding movement of said slide bar adapting said latch mechanism for operation from either side of

said door by means of suitable manual operators having actuating connection with said slide bar and a vertically movable, manually actuated locking block disposed between said two plates in adjacent relation with one end of said slide bar and operable from the interior of said automobile for interfering with and preventing said rectilinear movement of said slide bar thereby to stop said cams from releasing said prong wheels whereby said mechanism is frozen in a locked condition.

THOMAS C. DINGMAN.
